US0D1107570S

(12) **United States Design Patent** (10) Patent No.: **US D1,107,570 S**
(45) Date of Patent: ** Dec. 30, 2025

(54) **CONSTRUCTIVE LIGHT IMAGING DEVICE FOR 3D MEASUREMENT OR SURFACE INSPECTION**

(71) Applicant: **Shenzhen HANSWELL Technology Co., Ltd.**, Shenzhen (CN)

(72) Inventors: **Tao Huang**, Guangdong (CN); **Yuming Wei**, Guangdong (CN); **Yang Yang**, Guangdong (CN); **Aiting Zhai**, Guangdong (CN)

(**) Term: **15 Years**

(21) Appl. No.: **35/524,191**

(22) Filed: **Jan. 24, 2025**

(80) **Hague Agreement Data**

Int. Filing Date: **Jan. 24, 2025**
